[57] CLAIM

The ornamental design for a drapery valance, as shown and described.

DESCRIPTION

FIG. 1 is a front elevational view of a drapery valance showing my new design, and broken away to indicate indeterminate length;

FIG. 2 is a right end elevational view thereof, the left end being a mirror image;

FIG. 3 is a top plan view thereof;

FIG. 4 is a bottom plan view thereof;

FIG. 5 is a rear elevational view thereof;

FIG. 6 is a cross-sectional view thereof, taken on line 6—6 of FIG. 5;

FIG. 7 is a right front top perspective view thereof;

FIG. 8 is a left rear bottom perspective view thereof.

FIG. 1
